UNITED STATES PATENT OFFICE.

ABRAHAM POLLAK, OF NEW YORK, N. Y., ASSIGNOR TO SAMUEL KANNER, OF NEW YORK, N. Y.

MERCHANDISE-DISPLAY CARD.

Application filed May 13, 1924. Serial No. 712,919.

The invention relates to merchandise display cards and clips therefor of the character employed for holding fountain pens, pencils and other articles and permitting the same as sold to be individually, one after another, removed without disturbing the remaining articles on the card.

The object of my invention is to provide a display card adapted to hold fountain pens, pencils and the like with great firmness and without injury to the articles, and at the same time permit the articles to be instantly applied to and removed from the card by means which are not destroyed with each removal of an article and which admit of the convenient restoration of the article to the card whenever that course becomes necessary or desirable.

In carrying out my invention I provide a stiff paper card of adequate proportions and thereto detachably apply spring wire clips each having a loop or yoke inserted forwardly through a slot in the card, back members bearing against the back of the card and spring members intermediate said back members and the rear ends of the sides of said loop or yoke and which may be manually flexed forwardly toward the back of the card to enlarge the front exposure of the loop or yoke when an article is to be inserted into it, so that the article may be freely inserted, and which when released from the manual pressure flexing them forwardly, will resiliently act in a rearward direction to bind the loop or yoke against the article and press the same with great firmness against the front face of the card. When the article is to be removed from the card, the aforesaid spring members are manually flexed forwardly to project the loop or yoke forwardly from the article held by it, and thereupon the article becomes free and may be instantly withdrawn. The card and clips are not destroyed as used and may be repeatedly used for the display of the articles on sale.

The invention will be fully understood from the detailed description hereinafter presented, reference being had to the accompanying drawings, in which:

Fig. 1 is a front elevation, partly broken away, of a display card and clip embodying my invention, the same being shown as holding a fountain pen;

Fig. 2 is a vertical section through the

same, taken on the dotted line 2-2 of Fig. 1;

Fig. 3 is a back view of the card shown in Fig. 1 and illustrates the bearing members and spring members of the clip, these members being at the back of the card;

Fig. 4 is a horizontal section, partly broken away and on a larger scale, through the card and clip taken on the dotted line 4-4 of Fig. 1.

Fig. 5 is a corresponding section and illustrates the spring members as having been pressed toward the back of the card for projecting the loop or yoke of the clip forwardly to free, or to receive, the fountain pen, and

Fig. 6 is a perspective view of the spring clip detached from the card.

In the drawings, 10 designates a display card, 11 the spring clip applied thereto and 12 a fountain pen, which I have shown as indicating one class of articles to be held by the clip against the face of the card. I have only illustrated a portion of the display card and one clip, but it will be understood that the card 10 will be of sufficient proportions to receive a number of the clips 11 for holding a number of the articles 12 on the face of the card, all of the clips being alike and independent of one another, so that any one of the articles may be conveniently removed without disturbing the other articles held on the card.

The card 10 is a plain stiff card, which may be formed of any suitable material, and contains a narrow slot 13 cut through it and extending from the back to the front of the card.

The clip 11 is preferably formed from one integral rod of spring wire fashioned to provide a forwardly projecting loop or yoke 14, back bearing members 15 and spring members 16 which are intermediate of and connect the bearing members 15 with the ends 17 of the side arms of the loop or yoke 14 and carry said loop or yoke. The loop or yoke 14 is formed from the middle portion of the rod of wire, the bearing members 15 from the free end portions of the rod and the spring members 16 from portions of the rod intermediate the said middle portion and said free end portions, as will be understood on reference to Fig. 6.

When the clip 11 is applied to the card 10 the loop or yoke 14 is projected forwardly

- through the slot 13 until the bearing members 15 engage the back of the card, and under this condition the spring members 16 incline rearwardly from the bearing members 15 to the ends 17 of the side arms of the loop or yoke 14, which ends 17 are at the back of the card 10, being there initially held by the spring members 16 which incline rearwardly from the back of the card.
- 10 In the initial relation of the clip 11 with the card 10, the loop or yoke 14 does not project to its full extent through the slot 13 of the card and the frictional engagement of the walls of the slot with the loop or yoke is sufficient to maintain the clip on the card.
- 15

When a pen 12 or the like is to be inserted into the loop or yoke 14 so as to become held thereby against the face of the card 10, pressure is applied against the upper ends of the spring members 16 for projecting the loop or yoke 14 forwardly (Fig. 5) and thereupon the pen 12 may be very freely inserted endwise into said loop or yoke until the pen is in correct position on the card, whereupon the pressure on the members 16 is released, and at this time the resilient action of the spring members 16 retracts the loop or yoke 14 rearwardly against the pen 12 and causes said yoke to very firmly engage the pen and so strongly bind the pen in position against the card that the pen is prevented from slipping or sliding on the card and is held absolutely stationary.

20 35 When it is desired to remove the pen from the card, the upper ends of the spring members 16 are pressed forwardly to project the loop or yoke 14 further through the slot 13 and away from the pen, as shown in Fig. 5, and thereupon the pen is left entirely free to be withdrawn or even fall from the card.

40 It is to be noted that the pen is not scraped against the yoke 14 either when it is inserted into or removed therefrom.

45 50 The pressure to be exerted against the spring members 16 for projecting the yoke 14 forwardly to receive or release a pen, pencil or other article, may be applied directly thereto by the thumbs or by placing the card on its back on a counter or show case and pressing against the face of the card in the region of the ends of the slot 13.

55 In the drawings I have illustrated the bearing members 15 as lying between the tension members 16, and this is the preferred construction owing to the saving of space on the card 10 by this disposition of the members 15. The members 15 may, however, be bent outwardly from the lower

ends of the tension members 16 instead of 60 inwardly therefrom, and in that event the tension members 16 would lie between the members 15. I have made the clips in both of the constructions just indicated and find that the disposition of the members 15 shown in the drawings is preferable for the reason stated. I illustrate the yoke 14 as having a rounded outer end adapted to the cylindrical surface of the pen 12 but the outline of the yoke may naturally vary with 65 the shape of the article to be held.

I do not limit my invention to the precise embodiment thereof shown in the drawings, since I am aware that the same is capable of modification without departing 70 from the spirit of my invention and within the scope of the appended claims.

What I claim as my invention and desire to secure by Letters Patent, is:

1. A merchandise display card having a 80 slot therein and a spring clip having a bearing against the back of the card, a yoke extending forwardly through said slot and tension means engaging the back of the card for normally holding said yoke in a partly 85 retracted position and yieldable forwardly under pressure to allow the yoke to be projected further forward to receive the article to be held by it, the clip being firmly held against displacement from the card by the 90 article of merchandise which it supports.

2. A spring clip of the character described formed from a continuous piece of wire and having a central forwardly extending loop adapted to extend beyond the front surface 95 of a display card to embrace an article of merchandise, and the extremities of the wire being yieldable and reversely bent to engage the rear surface of the display card both above and below the loop.

100 3. A spring clip of the character described formed from a continuous piece of wire and having a central forwardly extending loop adapted to extend beyond the front surface of a display card to embrace an article of merchandise, and having downwardly-extending loops to engage the rear surface of the display card, said downwardly-extending loops terminating in resilient fingers which extend above the plane 105 of the central loop and press against the rear of the display card to normally draw said central loop rearwardly.

110 Signed at New York city, in the county of New York, and State of New York, this 6th day of May, A. D. 1924.

ABRAHAM POLLAK.
